UNITED STATES PATENT OFFICE.

EUGENE H. MAHLER, OF MILWAUKEE, WISCONSIN, ASSIGNEE TO COLUMBIA KNITTING
& MFG. COMPANY, OF MILWAUKEE, WISCONSIN, A CORPORATION OF WISCONSIN.

CAP.

Application filed June 5, 1923. Serial No. 643,522.

To all whom it may concern:

Be it known that I, EUGENE H. MAHLER, a citizen of the United States, residing at Milwaukee, in the county of Milwaukee and State of Wisconsin, have invented certain new and useful Improvements in Caps, of which the following is a specification, reference being had to the accompanying drawing, forming a part thereof.

10 This invention relates more particularly to soft brimless caps.

The main objects of the invention are to provide a light, comfortable and attractive cap, having an outwardly and upwardly folding back band and neck protector with inwardly and downwardly folding throat flaps at the ends which when unfolded, turned down and fastened under the chin will effectively protect the ears and back of the neck in cold or stormy weather and which when folded up will with a front reinforcing band, impart strength, stability and an attractive appearance to the cap; and generally to simplify, facilitate and improve 25 the construction and to increase the adaptability, convenience and comfort of such caps.

It consists in the construction, arrangement and combination of parts as herein-after particularly described and pointed out in the following claim.

In the accompanying drawing like characters designate the same parts in both figures.

35 Figure 1 is a perspective view of a cap embodying the invention, with the back band and one of the throat flaps unfolded and turned down; and Fig. 2 is a perspective view of the cap with the throat flaps folded inside of the back band and fastened therewith to the crown.

The cap, which may be made of knitted or other soft elastic fabric, comprises a crown *a*, an upwardly and inwardly folding back band and neck and ear protector *b*, and fastening and throat protecting flaps *c*, adjacent the ends of the band adapted to fold inwardly and downwardly inside of the upturned band.

40 The several parts enumerated may be and preferably are made from a single piece of fabric integrally with one another, as shown.

45 The fabric is cut to form a crown of the desired rounded shape, the curved edges of

the two sides or parts of the crown being joined together by a median seam *d*, extending from a point in the upper part of the back of the crown, as shown in Fig. 1, forwardly through the front side of the crown, as shown in Fig. 2.

To reinforce and give the crown a more attractive appearance, the cap is provided with a front band *e*, which is stitched along its lower edge to the crown and is preferably fastened at its upper edge or corners to the crown. Below the front band *e*, the extension of the crown forming the band *b*, is cut away or terminates, as shown in Fig. 1, a short distance in advance of the ends of the band *e*, so that when it is turned down, the eyes of the wearer will remain uncovered and when it is turned up, as shown in Fig. 2, it will overlap the ends of the front band.

50 The flaps *c*, which join and fold along the free sides of the back band *b* adjacent its front ends, are made of such width vertically that they will fold out of sight inside of the back band when it is turned up, as shown in Fig. 2, and when it is turned down, as shown in Fig. 1, will pass under and lap each other under the chin of the wearer, thereby affording protection to the throat besides serving to hold the downturned 55 back band in place snugly over the ears.

The flaps *c* are provided with suitable fastening means for holding them lapped together under the chin, such for example, as a button *f*, attached to one flap, and a button hole *g*, formed in the other, as shown.

The cap is also provided with suitable means for fastening the back band *b* and the flaps *c* in place when they are folded up against the crown, as shown in Fig. 2. For this purpose, the flaps are shown as provided on their inner sides adjacent their front and rear edges and the horizontal lines on which they fold, with members *h* of snap fasteners, and the crown is provided with complementary members *i* of such fasteners, which are completely concealed when the flaps are folded with the back band against the crown, as shown in Fig. 2.

When they are folded, the flaps *c* are completely concealed, and the back band *b* forms in effect a continuation of the front band *e*, giving the cap a substantial and attractive appearance for ordinary wear in mild or moderate weather.

Various changes in the details of construction of the cap may be made without departing from the spirit and scope of the invention as defined in the following claim.

5 I claim:

A cap comprising a crown having an upwardly foldable back band, a reinforcing front band secured along the lower edge thereof to the adjacent lower edge of said 10 crown, the ends of said front band extending rearwardly beyond the ends of said back band whereby the adjacent ends of said bands overlap when said back band is folded upwardly thereby forming in effect a continuation of said front band, said back band being provided with throat-protecting flaps, the vertical dimension of said flaps being such as to permit folding of the same out 15 of sight between said crown and said back

band when the latter is folded upwardly, 20 said flaps being provided on their inner sides adjacent their front and rear edges and adjacent the line on which they fold with fastening members, said crown being provided with complementary fastening 25 members adapted and arranged for coaction with said first-mentioned members when said back band is folded upwardly and said flaps folded between the latter and said crown whereby said members are completely 30 concealed and act to hold said back band and said flaps in their said respective folded positions, and means for fastening said flaps together in position to protect the throat 35 of the wearer.

In witness whereof I hereto affix my signature.

EUGENE H. MAHLER.
